UNITED STATES PATENT OFFICE

166,987

WIND DEFLECTOR

Henry L. Miller, Chicago, Ill., assignor to Sinko
Mfg. & Tool Co., a corporation of Illinois

Application February 13, 1952, Serial No. 18,506

Term of patent 7 years

(Cl. D14—6)

To all whom it may concern:

Be it known that I, Henry L. Miller, a citizen of the United States, residing at Chicago, county of Cook, and State of Illinois, have invented a new, original, and ornamental Design for a Wind Deflector, of which the following is a specification, reference being had to the accompanying drawing, forming a part thereof, in which:

Figure 1 is a front elevational view of a wind deflector; Fig. 2, a side elevational view; Fig. 3, a rear elevational view; and Fig. 4, a top plan view.

I claim:

The ornamental design for a wind deflector, as shown.

HENRY L. MILLER.
